UNITED STATES PATENT OFFICE.

GEORGE F. BROTT, OF WASHINGTON, DISTRICT OF COLUMBIA.

STEAM-GENERATOR.

SPECIFICATION forming part of Letters Patent No. 293,222, dated February 12, 1884.

Application filed June 15, 1883. (No model.)

To all whom it may concern:

Be it known that I, GEORGE F. BROTT, of Washington city, and District of Columbia, have invented certain new and useful Improvements in Steam-Generators; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to steam-generators, and to what is known as the "sectional" class. It has for its object simplicity of construction, safety from explosion, cheapness in first cost, readily repaired or cleaned, and to generate steam rapidly, and especially the separation of steam from the water, whereby priming is prevented.

Heretofore it has been found very difficult to prevent priming, or to separate the steam from the water in boilers wherein steam is rapidly generated, and when an active circulation of the water in the boiler is maintained, and by such rapid generation and circulation the water is kept in a constant state of agitation, the water passes over with the steam, which is very objectionable and dangerous. It is also well known that boilers have been constructed with some of their tubes adapted to be partially filled with water and steam, and that they are provided with escape-tubes, communicating with the different series through the same conduits, having divisions. This construction is also objectionable, as the water and steam pass out from the generating-tubes at the same end, and thus fail to separate. In mine I provide separate conduits for the steam from the steam-space of the tube, so that there is no danger of a mixture of steam and water passing off together, and thus priming is entirely avoided.

To prevent these objections and to overcome these difficulties, my invention consists in the means of feeding the boiler with water, by which circulation is maintained, and the egress of steam from the flues is facilitated, separated, and dried before leaving the boiler for use, and in other details of construction

which will be more fully hereinafter described, and pointed out in the claims.

Referring more particularly to the drawings, Figure 1 represents a vertical cross-section, taken on the line $x x$, Fig. 4. Fig. 2 is an outside end elevation, showing the arrangement of the flue-connections. Fig. 3 is an end view of the return-bends, and Fig. 3^a a view of the ends of two of the flues connected by an adjustable connection. Fig. 6^b is a sectional view of the tube and of an end cap connection, which is provided with a packing-piece, and which caps may be connected by independent tubes. Fig. 4 represents a longitudinal sectional elevation of the boiler-furnace and casing; and Fig. 5 rods provided with perforated disks which fit into the flues, said rods being suitably and snugly fitted within the tubes lengthwise, the object of which will be more fully hereinafter described. They may, however, be omitted, as the boiler will act equally well without them. Fig. 6 represents a detached sectional view of one of the series of sections of which the boiler is made up, and by which the products of combustion are made to pass backward to the rear of the boiler, and are thus prevented from directly impinging upon the steam-drums, and by which the said steam-drums are protected from the fierce heat of the flames. In this section I locate fire-brick tiles, cast-iron, or other refractory material between the upper portion of the drums and resting upon them; and while each section may be provided with these tiles, whereby the heat of the fire is made to go over and under each section, taking a circuitous course, yet I prefer to use them only on the section immediately below the steam-drums. Fig. 7 shows a modified form of the arrangement of the generating and steam tubes, as compared with Fig. 2. In this figure (7) a section of four generating-tubes is shown forming three spaces, and over such spaces I locate my fire-tile, which, with the generating drums or cylinders, forms a diaphragm or what may be termed a "horizontal partition."

A is the fire-box, of any suitable construction; and B the casing, which envelops the boiler, except at its ends.

C C are the ends of the boiler, which are preferably made in the form of a cap, and adapted to snugly fit over the ends of all the tubes, so that when access to the tube-connections is desired the cap can be readily removed. This cap also prevents the radiation of heat from the end of the boiler.

D represents a series of tubes or flues, which may be increased or diminished in number, 10 length, and size as necessity may require, according to the quantity of steam desired. The ends of these tubes preferably project outside the ends of the casing, and are connected together by return-bends E, which bends 15 also form caps, as clearly shown at Figs. 3 and 3^a. These caps are of peculiar construction and fittings. They are cast in pairs, and screw-threaded on their inner periphery, and provided near their upper surface with a connecting-tube, a, which tube forms the means of 20 communication between them, and is cast with them, if desired. When the caps are in position, and properly screwed upon the end of the flue, which is correspondingly screw-threaded on its exterior to receive it, the communicating connection is near the top, so that 25 a certain quantity of water must necessarily always remain in the tubes, except those intended for steam-space. Should it be desired, 30 these caps E may be cast singly, and connected by suitable connections, well known to the art; or such as shown at Fig. 3, which is made in sections and provided with a "union" and right-and-left-hand screw-threaded lock-nut.

35 It is obvious that the flue will be hotter than the cap, and thus expand more, so that the joints formed by the flue and the cap will always be tight and leakage thus prevented. The outside of the cap is angular, for the reception 40 of a wrench wherewith the cap may screw on and off; but when the double cap is used the flue is then turned and screwed into the cap. The caps are provided with screw-plugs b for the purpose of having access to the flues or 45 tubes, and which are generally known as "hand holes."

The rods F are provided with disks, (shown at Fig. 5,) and are inserted in the generating-tubes D. These disks are perforated, and are 50 for the purpose of preventing the water from rushing to one end of the flues, when the boiler is raised at opposite end, and when used for portable purposes, or on steamboats or launches.

It is well known that when one end of the 55 boiler is raised higher than the other the water will instantly rush to the lowest end, thus exposing the empty end of the flue to the action of the flame. To prevent this I locate disks at suitable distances in the generating-flue, or 60 in as many of them as have the exit-pipe attached to each section—three being the number required in this boiler—so that if the boiler is tilted the disks will retard the action of the water, and maintain it sufficiently in position 65 until the boiler is again righted. The perforations afford free escape for the steam and for

the water to circulate to all parts of the steam-generating flues. The rod F holds the disks in position and serves to locate and withdraw them when necessary. The horizontal series 70 of flues communicate with their next series by suitable connections, so that the water and steam may readily escape from one series to another.

G is a baffle-plate located in a suitable position to prevent the heat from directly escaping to the uptake J. By means of this baffle-plate the heat is kept longer in contact with the generating-flues by which it is imparted to the water therein. One, two, or more baffle-plates may be used, if desired. The tubes 75 not being expanded into a tube-sheet at their ends can expand or contract without injury.

The operation of my boiler is as follows: Water being fed through feed-pipe d, it fills 85 flue B' to a certain level. It then passes out of the opposite end of said flue to the next flue of the same section or series, which is also filled to the same level, and so on to the next of the series. The water then passes downward to the section below, and from one flue to the other, in like manner as the first series or section, and so on until all the sections are filled to the bottom, each maintaining its own level. The water then passes through every 95 flue from its entrance to the last one of the lower section, each flue having its supply, which cannot be drained off on account of the exit being at or near the top of each flue. Thus it will be readily seen that each independent generating-flue has its water-space and its steam-space. By this arrangement it will be readily seen that the tubes are never left without water in them, which can be shown by water-gage on the upper and lower 100 series. The steam generated in these tubes passes down with the water to the lowest section of tubes to the exit or steam tube, which I will now describe.

When the water and steam pass to the last 110 of the lowest section the steam then separates and passes up pipe H to the steam separating and superheating chambers I, of which there are a series or section precisely identical with the generating-flues in every respect, only 115 that no water enters these steam-chambers except what may pass over with the steam. However, should any water pass up into the 120 steam-chambers it would be trapped in the first chamber; or should any escape with the steam from the first chamber, it will be trapped in the second, so that when the steam reaches the next or last there is no possibility of any water being with it, so that it must be perfectly dry.

The water of condensation that may accumulate in the steam-chamber while the engine is at rest will readily generate into steam when the fire is started for operation. Thus I have a boiler made up of sections, each section 125 having a series of flues, and each flue having an independent water-and-steam space,

the boiler having also an independent section of steam-flues without water, by which the steam is thoroughly separated from the water and is also superheated, whereby the engine 5 is supplied with purely dried steam.

It is evident that the steam-space of each flue could be connected with the section of steam-chambers, if desired; but I prefer the plan shown. (Stand-pipe or steam-drum may 10 be attached where more steam-space is required.) It can be put together or taken apart by any engineer or gas-fitter, can be used with perfect safety from explosion, as by no possibility can superheated water flash into steam.

15 Having thus described my invention, what I claim as new, and desire to secure by Letters Patent, is—

1. The combination, in a steam-generator, of two or more series of steam-generating tubes 20 or flues, each of said tubes or flues being adapted to constantly remain partially filled with water by connecting the exit-tubes near the upper surface thereof and communicating with each other, the ends of said tubes being 25 connected in pairs by double-headers provided with plugs *b b*, substantially as described.

2. The combination, in a steam-generator, of two or more series or sections of tubes arranged above each other, the ends of each pair 30 of tubes united by a cap, which cap is screw-threaded, and has a circulating-tube near its upper surface cast therewith, and provided with plugs *b b*, as set forth.

3. A steam-generator composed of a series 35 or sections of generating tubes or flues, each of said tubes being adapted to be constantly

supplied with water, in combination with communicating tubes arranged in such manner that the water entering the upper section of generating tubes must traverse the entire 40 number of tubes, and having a separate series of steam-and-water-circulating tubes running in opposite directions, in the manner set forth and described.

4. The combination, in a steam-generator, 45 of two or more series or sections of tubes or flues with a steam-separating series, each of said series having communicating tubes connected to the upper portion of said tubes, and a steam-conveying pipe connecting the lower 50 series to the upper, substantially as described.

5. The combination of a boiler composed of sections, consisting of the lower series of tubes, which are partially filled with water, and having a steam-space, and being connected with the upper series of steam-drums, which are adapted to steam alone, and with the intermediate horizontal partition arranged below said drums and running partially back to the rear of the boiler, and arranged in such 55 manner as to protect the steam-tube drums from direct contact with the flame, and also form an outlet for the waste gases, smoke, &c., substantially as described.

In testimony that I claim the foregoing as 60 my own I affix my signature in presence of two witnesses.

GEORGE F. BROTT.
